DEVICE FOR HYPODERMIC INJECTIONS

Paul Kollsman, New York, N. Y.

Application December 20, 1947, Serial No. 792,993

7 Claims. (Cl. 128—220)

1

This invention relates to improvements in syringes for hypodermic or intramuscular injection of medicinal compositions. The invention has particular application to a novel type of injection device which, in effect, is a combination of an ampule and a syringe, or, in other words, an ampule containing a pre-determined volume of medicinal compositions, the ampule being equipped with a hypodermic needle so that the composition may be injected directly from the ampule without previous transfer to a separate syringe. Such devices are hereinafter sometimes referred to as "injector ampules." They are convenient and practical devices offering a great number of features and advantages over conventional syringes of the type requiring filling from a separate ampule.

Injector ampules are usually designed for one-time use, to be discarded after discharge of the fluid therefrom. They are supplied by the manufacturer, for example a pharmaceutical laboratory, filled with a pre-determined volume of a medicinal composition and are ready for immediate injection making it unnecessary to prepare, sterilize and fill a separate syringe.

Injector ampules are sterilized by the manufacturer before filling and all the parts coming in contact with the patient's body are maintained sterile by appropriate means which form part of the subject matter of the present invention. In addition to maintaining sterility, it is, of course, necessary to maintain an absolutely tight seal of the contents to prevent accidental discharge of fluid from the injector ampule.

It happens occasionally, particularly if injector ampules are carelessly handled, that an injector ampule is dropped whereby a force is exerted on the collapsible portions, for example, the piston or the plunger, in a direction to discharge fluid from the device. Relatively high pressures are set up in the fluid containing chamber of the injector ampule tending to blow off the seal of the injector needle or, at least, disturb the seal sufficiently to make subsequent contamination likely.

This invention provides means, improvements and specific constructions for maintaining a secure seal of all vital portions of the injector ampule so that the device is maintained tightly sealed against fluid discharge as well as tightly sealed against contamination even if dropped, excessively heated or cooled, or subjected to other conditions which would tend to disturb its essential properties.

The aforementioned and various other fea-

2

tures, advantages and objects of the invention will appear more fully from the detailed description which follows accompanied by drawings showing, for the purpose of illustration, preferred embodiments of the invention. The invention also consists in certain new and original features of construction and combination of elements hereinafter set forth and claimed.

Although the features characteristic of this invention which are believed to be novel will be particularly pointed out in the claims appended hereto, the invention itself, its objects and advantages and the manner in which it may be carried out may be better understood by referring to the following description taken in connection with the accompanying drawings forming a part of it in which

Figure 1 is a cross-sectional side view of an injector ampule embodying the invention;

20 Figure 2 is a cross-sectional side view of a modified form of device;

Figure 3 is a detailed cross-sectional side view on an enlarged scale of a multiple seal for the needle and front end of an injector ampule embodying the invention; and

25 Figure 4 is a detailed cross-sectional side view, on an enlarged scale, of a preferred form of sealing cap.

In the following description and in the claims, 30 various details will be identified by specific names for convenience. The names, however, are intended to be generic in their application. Corresponding reference characters refer to corresponding parts in the several figures of the drawings.

In the drawings accompanying and forming part of this application, certain specific disclosure of the invention is made for the purpose of explanation of broader aspects of the invention, but it is understood that the details may be modified in various respects without departure from the principles of the invention and that the invention may be applied to other structures than the ones shown.

45 The subject matter of this application is related to the subject matter of co-pending applications directed to devices of the general type disclosed herein.

Application Serial No. 792,991, filed December 50 20, 1947, discloses and claims a syringe in which the depth of insertion is automatically controlled and limited, and in which stop means are provided permitting measured partial discharge.

Application Serial No. 792,992, filed December 55 20, 1947, discloses and claims a syringe designed

for one-time use and so arranged that it cannot be reused.

Application Serial No. 792,994, filed December 20, 1947, discloses and claims a spring having a narrow visible and optically enlarged passage leading to the inner end of the needle to facilitate observation, and expulsion of, gas bubbles in the syringe chamber.

Application Serial No. 792,995, filed December 20, 1947, discloses and claims an improved form of non-creeping plunger seal.

The injector ampule shown in Figure 1 comprises a barrel 11 in which a plunger 12 is telescopically movable. The plunger 12 is tightly sealed with respect to the interior surface 13 of the barrel by a gasket 14 which rests in a groove 15 of the plunger and frictionally engages the interior surface 13 of the barrel 11.

In the illustrated form of syringe, the rear surface 16 of the plunger forms a movable wall of a chamber 17 adapted to contain a charge of medicinal fluid confined between the barrel 11 and the plunger 12.

A hollow injection needle 18, preferably of substantially uniform outer diameter is mounted in the plunger 12 and communicates with the chamber 17 through a hollow passage 19 extending through the plunger. The needle 18 projects from the front end surface 20 of the plunger a distance d which may be made equal to the depth to which the needle is to be inserted into the body tissue. The front end surface 20 may be made substantially flat and preferably has an area large enough to provide sufficient resistance for the ejection of a medicinal composition from the injector ampule without causing discomfort to the patient when force is exerted against the barrel 11 in a direction to collapse the chamber 17 to expel its contents through the needle 18.

The injector ampule shown in Figure 1 is primarily designed for filling with a medicinal fluid composition at the plant or laboratory of the producer, the volume of the fluid being sufficient for a single injection. After initial filling, the injector ampule is sealed to prevent accidental discharge of the fluid from the chamber 17 and also to maintain its vital portions sterile, particularly the needle 18 itself and the portion immediately surrounding the needle so that the needle is not contaminated by removal of its seal.

According to the illustrated embodiment of the invention, a cavity or recess 21 is formed in the front surface 20 of the plunger 12 immediately adjacent the needle. The side walls 22 of this cavity are preferably tapered to receive and tightly seal the end of a sealing cap 23 fitting over the needle 18.

The sealing cap 23 is preferably made of a relatively soft and elastic plastic material adapted to deform sufficiently to provide two seals, one at the tip of the needle and a further seal at the front end surface of the plunger 12. For this purpose, the cap 23 is preferably provided with a pre-formed, for example pre-molded, bore including two portions of different diameters. A front portion 24 is preferably made of a diameter slightly less than the outside diameter of the needle so that the needle, upon being forced into the front portion of the cap, causes the cap to expand slightly and form a pressure-tight seal near the point of the needle.

A rear portion 25 of the interior space of the cap 23 preferably has a diameter slightly larger than the outside diameter of the needle in order to fit easily over the needle when the cap is being

applied. The rearmost portion 26 of the cap 23 also may have an interior diameter slightly larger than the diameter of the needle. As the end of the cap is being forced into the cavity 21 of the plunger 12, the tapered side walls 22 of the cavity compress or deform the walls of the cap with the effect that the cap tightly engages both the side walls 22 of the cavity as well as the shank of the needle.

The frictional engagement of the cap 23 with the front portion of the needle 18, with the side walls 22 of the cavity 21 and with the shank of the needle is sufficient to prevent the cap from being removed or blown off accidentally, for example by dropping of the injector syringe in a direction to cause reduction of the chamber volume 17. The relatively high pressure which is being built up at the moment of impact acts on only a very small area of the sealing cap 23, that is on an area whose diameter is equal to that of the needle. This area is very small and even high pressures developed in the chamber 17 are not sufficient to cause the frictionally held cap from being blown off.

The end of the cap 23 seating in the cavity 21 is maintained sterile and is protected against contamination by reason of its pressure tight seat in the plunger 12. When the cap 23 is removed from the needle 18 in order to prepare the injector ampule for use, the portion of the cap 23 which slides along the needle is the rear portion which was preserved sterile. In this manner contamination of the needle is effectively prevented. Contact of the syringe with the patient's skin immediately adjacent the needle is prevented by the recess 21 in the plunger surrounding the needle.

In sealed condition, the device serves as an ampule for storage of the medicinal fluid and may be readied for immediate use simply by removal of the sealing cap 23.

Small air bubbles accidentally trapped in chamber 17 may easily be removed by placing the filled syringe in an upright position causing the bubbles to rise and collect near the passage 19. Slight telescoping movement of the plunger 12 with respect to the barrel 11 forces the bubbles out through the passage 19 and the needle 18.

The injector syringe may be used as follows: After removal of the sealing cap 23, the device is ready for use. It is preferably applied to the body of a patient by grasping it at the barrel 11 which provides a finger grip surface or portion 27. The point of the needle 18 is placed on the patient's skin and pressure is then exerted in the direction of the needle 18 to force the needle into the body tissue. This pressure does not cause any discharge from the syringe because of an initial considerable amount of friction between the plunger gasket 14 and the barrel surface 13, this friction being relatively great while the plunger is at rest and equivalent to a multiple of a force required for inserting the needle into the body tissue.

When the front end surface 20 of the plunger comes to rest on the patient's skin, the pressure exerted at the barrel 11 is opposed by an equal pressure of the skin against the front surface 20. This opposing force is sufficient to overcome the friction of the gasket 14. The barrel 11 then moves telescopically over the plunger causing the fluid to be discharged through the passage 19 and the needle 18 into the patient's body tissue.

Figure 2 illustrates a modified form of injector

ampule comprising a barrel 30 within which a plunger 31 is telescopically movable. The plunger has an enlarged finger operable grip portion 32 for convenient handling. A movable seal or membrane 33 which may be separate from the plunger 31 is telescopically movable in the barrel 30 and forms a seal for the fluid chamber 34 against the plunger 31.

An injection needle 35 is mounted in the front end 36 of the barrel and is surrounded by a cavity or recess 37 having tapered walls 38.

A sealing cap 39 covers the needle 35. The cap 39 has a narrow bore front portion 40 tightly fitting over the point of the needle and a wider rear portion 41 of an interior diameter slightly larger than that of the needle. The rear portion 41 of the cap fits frictionally and tightly into the cavity or recess 37 with its end portion 42 usually sufficiently compressed by the tapered walls to engage the outside of the needle 35 also.

A modified form of sealing cap is illustrated on an enlarged scale in Figure 3 showing also the front end of an injector syringe. The sealing cap 45 is made of relatively soft resilient plastic material and has a front portion 46 tightly fitting over the front end of the needle 47, the outside diameter of the needle being preferably slightly larger than the inside diameter of the front portion 46 of the cap so that application of the cap over the needle causes the cap slightly to bulge at the portion where a tight seal is effected as is also apparent from the drawings.

The rear portion 48 of the cap fits loosely over the needle and its end portion 49 is adapted to be frictionally and pressure-tightly held in a tapered hole 50 in the front end 51 of the injector ampule.

A long and slender rod 52, preferably of metal, for example a stainless steel wire, is molded or otherwise secured in the front portion 46 of the cap and extends through the channel or bore of the needle 47 into the chamber 53 of the injector ampule containing the medicinal fluid.

The rod 52 serves a double purpose. It prevents the needle passage from clogging up by reason of contact of the medicinal fluid with the metallic needle 47 so that clearance of the needle passage is insured after removal of the sealing cap 48 and the rod.

The rod 52 further constitutes a flow resistance of considerable magnitude resulting in added sealing protection. If abnormally high pressures are built up in the chamber 53, for example by accidental dropping of the injector ampule, no appreciable pressure increase is experienced at the needle point during that brief period since pressure builds up only very slowly along the needle passage through which the rod 52 extends by reason of the great flow resistance of the constricted passage. Thus, a low pressure seal at the needle point is sufficient to resist temporary high pressures in the chamber 53.

The form of sealing cap illustrated in Figure 3 thus affords triple protection. Two pressure tight seals are formed at the tip and at the base of the needle at 46 and 49, respectively, the latter seal also insuring sterility of the area immediately surrounding the needle and preventing contamination of the needle by removal of the sealing cap therefrom. In addition, the rod 52 virtually constitutes a seal in itself by reason of closing the needle passage almost entirely.

The tapered sealing surface in the front end

of the housing of the injector ampule is also adapted to receive the nozzle of a filling duct through which the injector syringe is first filled by forcing the medicinal fluid under pressure into the chamber 17, 34, or 53, respectively, through the needle.

A specific form of construction for the sealing cap, preferred because of its simplicity and ease of manufacture, is shown in Figure 4.

The cap comprises a tubular portion 54 of a suitable plastic material, preferably made in the form of tubing from which pieces of appropriate length are cut. The inner diameter of the tubing is slightly narrower than the outside diameter of the needle over which it is intended to fit. For example, for a needle having an outside diameter of 0.035", tubing of approximately 0.032" inside diameter may be used, the yieldability and elasticity of the plastic material being such that the tubing may be slipped over the needle without an undue application of force. A rod or stylus 55 extends inside the tubing, the outside diameter of the rod being slightly less than the inside diameter of the needle passage. The rod 55 has an enlarged end or head 56 which fits tightly within the tubing 54 and seals its front end. The tubing may additionally be squeezed together and sealed at 57, either by application of a suitable adhesive or solvent, or by application of heat, such procedures of sealing metal to plastic being known to the art.

The sealing cap thus made is easy and inexpensive to manufacture and forms a reliable seal for injector ampules and syringes.

Obviously, the present invention is not restricted to the particular embodiments herein disclosed. Numerous modifications, additions, omissions, substitutions and various other changes may be made, for example by making parts separate or integral, without departing from the spirit and the essence of the invention, as defined in the appended claims. All such changes will suggest themselves to persons skilled in the art after consideration of this disclosure and do therefore not involve a departure from the spirit and the teachings of the invention.

What is claimed is:

1. A combination ampule and syringe for storing and injecting a predetermined volume of a medicinal fluid comprising, a barrel member; a plunger member movable in said barrel member and forming a variable volume chamber therewith adapted to contain a charge of medicinal fluid; a hollow injection needle mounted in the front end of one of said members, said one member being shaped to provide a tapered sealing surface about said needle; a cap of plastic resiliently deformable material sealing the point of said needle and seating pressure-tightly against said tapered sealing surface about said needle; and a rod in said cap extending through said hollow needle towards said chamber.

2. A combination ampule and syringe for storing and injecting a predetermined volume of medicinal fluid comprising, a barrel member; a plunger member movable in said barrel member and forming a variable volume chamber therewith adapted to contain a charge of medicinal fluid; a hollow injection needle mounted in the front end of one of said members, said needle projecting from the front end surface of said one member, said one member being shaped to provide a tapered sealing surface about said

needle; and a sealing cap pressure-tightly fitting on said sealing surface, said cap having a further sealing portion pressure-tightly engaging the point of said needle.

3. A combination ampule and syringe for storing and injecting a predetermined volume of medicinal fluid comprising, a barrel member; a plunger member movable in said barrel member and forming a variable volume chamber therewith adapted to contain a charge of medicinal fluid; a hollow injection needle mounted in the front end of one of said members, said needle projecting from the front end surface of said one member, said one member being shaped to provide a tapered internal sealing surface about said needle; and a sealing cap pressure-tightly fitting on said sealing surface, said cap having two portions of different internal diameter, a narrower portion adapted to engage and pressure-tightly seal said needle near its point, and a wider portion loosely fitting about the rearward portion of said needle.

4. A combination ampule and syringe for storing and injecting a predetermined volume of medicinal fluid comprising, a barrel member; a plunger member movable in said barrel member and forming a variable volume chamber therewith adapted to contain a charge of medicinal fluid; a hollow injection needle mounted in the front end of one of said members, said needle projecting from the front end surface of said one member, said one member being shaped to provide a tapered sealing surface about said needle; a sealing cap pressure-tightly fitting on said sealing surface, said cap having two portions of different internal diameter, a narrower portion adapted to engage and pressure-tightly seal said needle near its point, and a wider portion loosely fitting about the rearward portion of said needle; and a rod mounted in said cap adapted to extend through said hollow needle into said chamber.

5. A combination ampule and syringe for storing and injecting a predetermined volume of a medicinal fluid comprising, in combination, a barrel member; a plunger member telescopically fitting into said barrel member and forming a variable volume chamber therewith adapted to contain a charge of medicinal fluid, one of said members having a front end surface adapted to engage, and rest against, the body portion of a patient into which the fluid is to be injected; sealing means for sealing the plunger member with respect to the barrel member; a hollow injection needle mounted in one of said members communicating with said chamber, said needle projecting from said front end surface, said surface by resting against the body portion of the patient limiting the depth to which the needle is insertable, one of said members having a finger grip portion for manual operation of the syringe by pressure exerted at said finger grip

portion in the direction of said needle, said one member having a cavity in its front wall surrounding said needle; and a sealing cap pressure-tightly seating in said cavity, said cap having two portions of different internal diameter, a narrower portion adapted to engage and pressure-tightly seal said needle near its point, and a wider portion loosely fitting about the rearward portion of said needle.

10 6. A combination ampule and syringe for storing and injecting a predetermined volume of a medicinal fluid comprising, a barrel member; a plunger member movable in said barrel member and forming a variable volume chamber therewith adapted to contain a charge of medicinal fluid; a hollow injection needle mounted in the front end of one of said members, said one member being shaped to provide a tapered sealing surface about said needle; a tubular sealing member snugly fitting over said needle and seating pressure-tightly against said sealing surface; and a rod in said sealing member extending into said needle, said rod having an enlarged end portion tightly fitting into said tubular sealing member and closing the end of the sealing member adjacent the point of the needle.

15 7. A combination ampule and syringe for storing and injecting a predetermined volume of a medicinal fluid comprising, a barrel member; a plunger member movable in said barrel member and forming a variable volume chamber therewith adapted to contain a charge of medicinal fluid; a hollow injection needle mounted in the front end of one of said members, said one member being shaped to provide a tapered sealing surface about said needle; a tubular sealing member of plastic material snugly fitting over said needle and also engaging said one member at said sealing surface; and a rod in said sealing member, said rod extending into the hollow passage of the needle and having an enlarged end portion tightly fitting into said tubular sealing member to close the other end of the sealing member adjacent the point of the needle.
